UNITED STATES PATENT OFFICE.

DAVID S. HULFISH, OF TORONTO, ONTARIO, CANADA.

AUTOMATIC TELEPHONE SWITCH AND SYSTEM.

1,427,473.

Specification of Letters Patent. Patented Aug. 29, 1922.

Application filed December 8, 1917. Serial No. 206,189.

To all whom it may concern:

Be it known that I, DAVID SHERRILL HULFISH, a citizen of the United States of America, residing at Toronto, in the county 5 of York and Province of Ontario, Canada, have invented new and useful Improvements in Automatic Telephone Switches and Systems, of which the following is a specification.

10 My invention relates to improvements in automatic electrical switches and in the uses thereof, and the objects of my invention are to provide an improved power-driven electrically controlled switch, improved circuit systems for connecting the switches for service, and improved methods of operation, as illustrated in the accompanying drawings, and as described herein.

In the drawings: Fig. 1 shows section of 20 switch and tag bank on line 1—1 of Fig. 2. Fig. 2 shows front elevation of switch with tag bank omitted. Fig. 3 shows driving devices. Figs. 4, 5, 6, 7 and 8 unite to form a large circuit diagram, and show a 25 system of circuits for giving telephone service. Fig. 9 shows an amplification of parts of the circuit diagram.

Referring to Figs. 1 and 2: The movable brushes 201, 202 carried by insulation 30 upon brush shaft 203 engage the under surfaces of eligible tags 204, held fixed in the tag bank upon insulating plate 206. The tag bank comprises a plurality of levels of tags, many known methods of construction 35 being available. Each level has two brushes as shown, each brush having a feed tag 205 fixed in the tag bank. The feed tags are in the level of the eligible tags. The brushes shown, 201 and 202, engage the 40 under surfaces of the feed tags as well as of the eligible tags, hence the brush may pass the feed tag. Alternate levels have brushes above instead of below. The tag bank comprises tag-bank plates 206 and tags 204, 205, rigidly held together and 45 attached to fixing plates 207, the fixing plates being then fixed upon vertical supporting rack bars 208. Dowels 255 are fixed in parts 207 and pass through holes 50 in switch body-plate 209. The faces of parts 207 engage the back face of part 209.

Body plate 209 has flanges 210 supporting brush carrying shaft 203 and armature shaft 211. The brush carriage comprises

shaft 203, hub 212, ratchet 213, brush spacers 214 of insulation, feed-tag guides 215 of insulation, brushes 201, 202, clamp 216, and screws 217 which thread into hub 212 and clamp all parts. The alinement of brushes is attained by insulating dowels 218.

Main spring 219 attached to hub 212 and flange 210 turns brush carriage when double pawl 220 permits and brushes pass from tag to tag, advancing a half-step when armature 221 has been attracted and the remaining half-step when armature has been returned to normal by armature spring 256. A brush may be shaped to engage a tag while the armature is normal or while the armature is attracted, or both. A brush at 70 one end of its travel may rest upon its own feed tag. Armature carrier 222, carrying armature 221 and double pawl 220, is carried by armature shaft 211 between spacing sleeves 223, and is pulled by spring 256. 75 Magnet support 224 supports magnets 225 and clutch-arm guide 226. Clutch arm 227 is pivoted upon ratchet 213, rests upon wing 228 of guide 226 and is drawn against the guide by spring 229. Clutch tooth or 80 thrust member 230 is clamped upon drive shaft 231. Drive shaft 231 oscillates continually through a predetermined angle. Normal switch 232 comprises two contact springs mounted upon bracket 233 upon 85 supporting bar 208, tending to open, held closed by part 226 and spring 234. Clutch arm 227 is shown in three positions, solid line in normal position, dash line awaiting restoration, and dot-dash line at close of 90 thrust of clutch hook. Parts 230 and 236 are shown in dot-dash line in their positions at the time part 227 occupies its dot-dash position.

The operation of the switch is as follows: 95 Repeated electrical currents through magnets 225 operate armature 221 repeatedly and brush carriage moves step-by-step until a desired selective position is attained. For restoration to normal, further repeated 100 or intermittent currents operate armature, brush carriage moves, clutch arm 227, propelled by ratchet 213, passes its corner 235 beyond guide 226, spring 229 draws clutch arm into path of clutch tooth 230, as 105 shown in dot line in Fig. 2. The clutch tooth engages the clutch arm and forces the clutch arm to the position shown in dot-

dash line in Fig. 2, thus restoring the brush carriage to normal. The clutch-arm corner 235 has forced guide 226 to position shown in dot-dash line, thus opening normal switch 232 as shown in dot-dash line. Tooth 230 retires and disengages itself from arm 227, spring 234 pulls guide 226 to normal position, closes normal switch 232 and lifts arm 227 to normal position as shown in solid line. By determining the dimension of the double pawl 220 between the faces which engage the ratchet, the relative lengths of the first and second steps of the ratchet and brushes for each ratchet 15 tooth may be determined.

The devices for driving the shaft 231 are as follows: Motor 236 (Fig. 3) drives power wheel 237, link 238 and driving arm 239 upon shaft 231. The shaft 231 oscillates continually as indicated by the double-headed curved arrow.

Switches of the type described may be organized by electric circuits and associated with telephones and callsenders to give an automatic telephone service. A system of circuits is shown in Figs. 4, 5, 6, 7 and 8, the figures uniting at the margins where conductors of similar labels meet. Each switch has tag-levels sufficient in number for its requirements, the levels being numbered at the ends. The tags in each level are numbered below. Each tag is represented by a circle; each brush by a rectangle united by a conductor-line to its feed tag. Brushes shown between tags will engage the tag at the half-step. The callsender may be of any known type, the electrical contact members being arranged as required.

In the drawings, numbers under 100 are location numbers for identifying contact tags. A tag is identified by giving first the label of the switch, then the level number, then the tag number in the level; thus, 103-2-6, meaning switch 103, level 40 2, tag 6. A brush is identified by the location of its feed tag. Switches 101 and 105 have some of their levels omitted from the diagram. Switch 101 engages its clutch members for mechanical restoration when 45 its brushes reach tags 13-and-25, the brushes then being restored to tags 1-and-13. Switches 102, 104 and 105 restore from 12-and-24 to 0-and-12. Switch 103 restores from 11-and-23 to 0-and-12. 50 The automatic switches are grouped into "sets" or "divisions", which are duplicated as required to serve the traffic. A "set" of switches comprises pilot 103, groupfinder 102, linefinder 101, register 104 and final 55 connector 105.

Each telephone line has two relays, line relay 149 and cut-off relay 148. The line relays pertaining to each searching brush of the linefinder 101 have a common wire 60 65 305 to the groupfinder, identifying the line-

finder group among the groupfinder tags. Circuits are referred to by numbers, C1, C2, and so on.

The operation is as follows:

A lifted receiver at telephone 106 by its 70 hookswitch closes C1 and charges telltale relay 147, line relay 148 and starting relay 146.

C1. "Line circuit".—(Pilot brushes on tags 1—and—13). Battery, helix of 147, 75 points of 148, linewidth 301, telephone 106, linewidth 302, points of 148, helix of 149, helix of 146, earth.

Starting relay 146 closes C2 to charge groupfinder magnet 122 repeatedly as C2 is 80 interrupted repeatedly by brush 102-4-25 at the half-step, until brush 102-1-25 closes searching circuit C3. C3 then charges test relay 138 which opens C2 and closes C4 to advance the pilot brushes to open both 85 C2 and C3, the relay 138 then opening C4. The pilot brushes pass to tags 2—and—14.

C2. "Groupfinder drive".—(Pilot 1-13). Battery, groupfinder magnet 122, normal switch 112, interrupting brush 102-4-25 90 and tags 12—to—22, wire 324, 103-5-13, wire 354, points of 138, wire 344, 103-4-13, wire 306, points of 146, earth.

C3. "Groupfinder test".—(Pilot 1-13). Battery, helix of test relay 138, wire 350, 95 103-2-13, wire 327, brush 102-1-25, tag 102-1-14 or analogous tag identifying the line-group containing the calling line, wire 305, points of 149, earth.

C4. "Pilot magnet".—(Pilot any position). Battery, pilot magnet 123, normal switch 113, wire 349, points of 138, earth.

With pilot brushes on tags 2—and—14, starting relay 146 closes C5½ and then C5 to charge linefinder magnet 121 repeatedly 105 as C5 is interrupted repeatedly by brush 101-20-25 at the half-step, until brush 101-17-0, (or analogous brush selected by the groupfinder, the several eligible sets of tags in 102 being connected to brushes on 110 eligible levels in 101 in manner analogous to tags in the eligible set 102-1-2, 102-2-2, 102-3-2, 102-4-2,) engages wire 364 of the calling line on tag 101-20-4 and closes searching circuit C6. C6 then charges 115 test relay 138 which opens C5 and closes C4 again to advance the pilot brushes to open both C5 and C6. The pilot brushes pass to tags 3—and—15, and charge the cut-off relay over C7.

C5½. "Linefinder drive".—(Pilot 2-14). Battery, linefinder magnet 121, normal switch 111, brush 101-20-25, tag 101-20-13, wire 616, 103-1-14, wire 354, points of 138, wire 344, 103-4-14, wire 306, points of 146, earth.

C5. "Linefinder drive".—(Pilot 2-14). Battery, linefinder magnet 121, normal switch 111, brush 101-20-25 and tags 14-24, wire 325, 103-5-14, wire 354, points 125 130

of 138, wire 344, 103—4—14, wire 306, points of 146, earth.

C6. "Lineline test".—(Pilot 2—14). Battery, helix of 138, wire 350, 103—2—14, 5 wire 326, brush 102—4—0 and tag to which that brush has been adjusted, brush 102—20—0 moving until wire 364 of calling line is engaged upon tag 101—20—4, wire 364, points of 149, earth.

10 C7. "Calling guard".—(Pilot 3—15 to 6—18). Battery, resistance 134, 103—6—3, wire 313 through 102 and 101 as adjusted to wire 363, helix of 148, earth.

With pilot brushes on tags 3—and—15 15 a loop C8 is formed to the calling telephone through signal relay 141 and holding relay 142, charging those relays.

20 C8. "Calling loop"—(Pilot 3—15). Battery, helix of 142, wire 336, 103—4—3, wire 311, through 102 and 101 as adjusted to wire 361, linewire 301, callsender conductor springs 151, 152, telephone 106, linewire 302, wire 362, through 101 and 102 as adjusted to wire 312, 103—5—3, wire 340, helix of 25 141, earth.

The next action is to adjust the register or "tens" switch 104 to the selective position required to select ultimately the desired line to be called, by action of the callsender 30 at the telephone, and then to shift the pilot brushes as a "changeover" switch.

35 The callsender when operated moves 150 to engage 151 and to disengage 152 from 152 a predetermined number of times, meaning 35 while holding shunt switch 154 closed during the entire operation. Each movement of 150 forms a circuit to earth C8, to hold holding relay 142 and then breaks C8 to release signal relay 141. Signal relay 141 40 thus is released several times rapidly to effect the adjustment of tens switch 104 and changeover of pilot 103.

To adjust switch 104, relay 141 closes C9 repeatedly. To shift switch 103 at the 45 end of adjustment of 104, relay 141 sends by C10 a set of impulses to end-signal relay 139 and switch 104 also sends by C10.1 a set of impulses to relay 139, the two sets of impulses being concurrent but out of 50 phase so that the points of 139 are held operated until after impulses cease in C10. When 139 is finally released, it closes C11 to charge relay 138 which in turn closes C4 again to advance the pilot brushes. An impulse 55 in C10 ceases when 141 is re-charged but the companion impulse in C10.1 continues until 124 in C9 has been magnetically discharged, until the armature 219 of 124 has been released and retracted to permit 60 dog 220 to clear from the tooth of ratchet 213, and until mainspring 219 has moved the brushes as a mass so far that brush 104—6—0 has broken contact from its tag; this succession in time in the termination of 65 the two companion impulses I am describ-

ing briefly by saying that the impulses are concurrent but out of phase. The two relays 141 and 139 are preferably alike in mechanical construction, the delay by phase displacement of the impulses to 139 being 70 such that in a series of signals 141 is re-discharged to re-charge 139 before 139 can close C11.

C9. "Tens impulses".—(Pilot 3—15). Battery, register magnet 124, normal switch 75 114, wire 316, 103—6—15, wire 355, points of discharged 141, points of charged 142, earth.

C10. "Endsignal relay".—(Pilot 3—15). Battery, upper helix of 139, wire 345, 80 103—9—3, wire 309, wire 355, points of 141, points of 142, earth.

C10. 1. "Endsignal auxiliary".—(Pilot 3—15). Battery, lower helix of 139, wire 317, 85 103—10—3, wire 399, brush 104—6—0 and tags 1 to 11 at half-step, and to earth over wire 304.

C11. "Endsignal".—(Pilot 3—15). Battery, helix of 138, wire 350, 103—2—15, wire 318, tags and brush 104—5—0, wire 90 319 points of discharge 139, earth.

Pilot brushes pass to tags 4—and—16 and prepare circuits for the adjustment of the final connector or "units" switch, 105, the circuits being C12, C10, C10.2 and C13, and the action being analogous to the action in adjusting switch 104. Callsender spring 151 discharges 141 repeatedly. Relay 141 sends impulses by C12 to magnet 125 and by C10 to relay 139, concurrently with impulses sent by C10.2 from switch 105 to relay 139. Relay 139 then closes changeover circuit C13 through switch 105 to shift switch 103.

C12. "Units impulses".—(Pilot 4—16). 105 Battery, final connector magnet 125, normal switch 115 wire 329, 103—6—16, wire 355, points of discharged 141, points of charged 142, earth.

C10.2. "Endsignal auxiliary".—(Pilot 4—110 16). Battery, lower helix of 139, wire 317, 103—10—4, wire 399, brush 105—20—0 and tags 1 to 11 at half-step, and to earth over wires 307 and 304.

C13. "Endsignal".—(Pilot 4—16). Bat- 115 tery, helix of 138, wire 350, 103—2—16, wire 370, tags and brush 105—19—0, wire 319, points of discharged 139, earth.

Relay 138, charged by C13, closes C4 again and passes pilot brushes to tags 120 5—and—17. The selected line being not busy, the uncharged busy-test relay 137 charges relay 138 by C14 and 138 by C4 passes pilot brushes to speaking position on tags 6—and—18, where by C15 the cut-off 125 relay 107 of the selected line is charged.

C14. "Idle test".—(Pilot 5—17). Battery, helix of 138, wire 350, 103—2—17, wire 375, points of 137, wire 615, secondary winding of tone induction coil 136, earth. 130

C15. "Answering Guard".—(Pilot 6—18). Battery, resistance 174, wire 374, 103—3—6, wire 323, through switches 104 and 105 as adjusted to wire 353, helix of 107, earth.

5 The selected line is rung by operating the ringing key 153 at the calling telephone. By earth upon wire 301, C8½ is formed to hold relay 142 and relay 141 is shunted and releases its armature, closing C16 to charge 10 ringing relay 144. Ringing relay 144 closes C17 to connect ringing generator 145 through the selected line.

C16. "Ringing relay".—(Pilot 6—18). Battery, helix of 144, points of charged relay 142, wire 377, 103—6—18, wire 355, points of discharged 141, points of charged 142, earth.

C17. "Ringing".—(Pilot 6—18). Ringing generator 145, wire 609, points of 144, 20 wire 338, 103—1—6, wire 321, through 104 and 105 as adjusted, to wire 351, condenser and callbell of telephone 108, wire 352, switches 105 and 104 as adjusted, wire 322, 103—2—6, wire 337 and through helix of 25 140 to first earth; branching from wire 337 through wire 348, condenser 132, wire 384, 103—8—6, 103—8—0, 103—5—0, and wire 340 and helix of 141 to second earth; branching from 103—5—0 through 103—5—6, wire 312, switches 102 and 101 as adjusted, wire 362, wire 302, calling telephone hookswitch, wire 301, switches 101 and 102 as adjusted, wire 311, 103—4—6, 103—4—0, wire 336, helix of 142 to battery and to third 35 earth; branching from 103—4—0 through 103—7—6, wire 385, condenser 131, wire 347, helix of 143 to battery and to fourth earth.

Lifting the receiver upon the selected line 40 closes a loop C18 through answering relay 140 and answering feed spool 143. The circuit for speech transmission C19 is over conductors of C8 and C18 through condensers 131 and 132.

C18. "Answering loop".—(Pilot 6—18). Battery, helix of 143, points of 144, thence over C17 to "first earth".

C19. "Speaking".—(Pilot 6—18). Includes C8 and C18, except 140, 141, 142, 143, 50 and connected together as follows: From 103—5—0, through 103—8—6, wire 384, condenser 132, wire 348 to wire 337; and from 103—4—0, through 103—7—6, wire 385, condenser 131, wire 347, points of 144 and to 55 wire 338.

I divide the action of the automatic switches into two parts, first, "operation", by which a telephone call is given service, and second, "restoration", by which used 60 switches are returned to their normal condition of waiting, in readiness for service upon a subsequent call.

In using the switches herein described, the method of restoring each switch is to ad-

vance the switch electrically to its ultimate 65 position, then to engage its mechanical power source and to restore it mechanically to its primary position. If all switches were restored simultaneously, C7 and C8 might be formed to certain lines through 70 switches 103, 102, 101, while C15 and C18 might be formed to certain lines through switches 103, 104, 105, all of which might be found objectionable. To obviate this condition, I provide a method of restoring in 75 which all switches are rendered independent in their "operating" circuits but dependent in certain "restoring" circuits, then are restored serially or in groups in such order and in such manner that no "operating" circuit is formed to any telephone line during the action of "restoring", and ultimately are rendered again electrically dependent in their "operating" circuit by the final act of restoration. In this method of restoration, 80 the circuits in each switch which might lead to telephone lines are held open in a second switch while the prime switch is returning to normal.

The calling telephone line initiates the release of the switches by hanging the receiver upon the hook, breaking C8 and releasing holding relay 142 which by its points closes C20 to advance the pilot brushes. C20 charges relay 138 which by C4 charges pilot 95 magnet 123. The pilot brushes leave tags 6—and—18 and break all "operating" circuits.

C20. "Pilot release".—(Pilot in any position from 3—15 to 9—21). Battery, helix 100 of 138, wire 350, brush 103—3—25 and tags 15 to 21, wire 360, points of 142, earth.

The circuit C20 is interrupted at the half-step on brush 103—3—25 and the pilot brushes advance to tags 10—and—22, where 105 C21 advances the linefinder 101 to position 13—and—25 and C22 advances switches 102, 104, 105 to position 11—and—23 in each switch. When brushes in switches 102, 104, 105 have reached tags 23, occupying then 110 their sub-restoring positions, they close C23 which charges relay 138 which by C4 advances the pilot brushes to tags 11—and—23.

C21. "Linefinder release".—(Pilot 10—22). Battery, linefinder magnet 121, normal 115 switch 111, brush 101—20—25 and tags 14 to 24, wire 325, 103—8—22, earth.

C22. "Switch release".—(Pilot 10—22). Battery, final connector magnet 125, normal switch 115, brush 105—20—25 and tags 13 120 to 22, wire 308, 103—10—22, earth. Also, battery, register magnet 124, normal switch 114, brush 104—6—25 and tags 13 to 22, wire 315, 103—9—22, earth. Also, battery, groupfinder magnet 122, normal switch 112, 125 brush 102—4—25 and tags 12 to 22, wire 324, 103—7—22, earth. If switch 104 has not been operated from normal C22 will not op-

erate that switch. If switch 105 has not been operated from normal, C22 will not operate that switch.

C23. "Pilot clutch".—(Pilot 10—22).

- 5 Battery, helix of 138, wire 350, 103—3—22, wire 310, 105—17—23, wire 320, 104—2—23, wire 386, 102—3—23, and earth over wire 328. If switch 104 has not been operated from normal, C23 will be through 104—2—12. If switch 105 has not been operated from normal, C23 will be through 105—17—12.

In the linefinder 101, with brushes on tags 13—and—25, shoulder 235 passes member 226 and 227 awaits engagement of 230. In the pilot 103, with brushes on tags 11—and—23, shoulder 235 passes member 226 and 227 awaits engagement of 230. This difference may be attained by variant lengths 20 of arm 227 on the sundry switches and by adjusting the angular position of guide 226. With the next advancing swing of shaft 231 and hooks 230, the linefinder 101 is restored to its normal position with brushes 25 on tags 1—and—13, while the pilot 103 is restored mechanically to a pre-normal position beyond its electrical normal position, and stops with its brushes on tags 0—and—12. During the reverse movement of the line- 30 finer brushes, no circuit is completed to any line, because I do not connect any linefinder brush touching a telephone line wire to any groupfinder tag upon which a groupfinder brush rests, tags 102—1—11, 102—2—11, 35 102—3—11 being left vacant. During the reverse movement of the pilot brushes, no circuit is completed to any line in the final connector, because switches 104 and 105 are motionless and I arbitrarily leave vacant 40 in the final connector switch the tags to which conductors 311, 312, 313 are extended in that adjustment of switches 104 and 105. Thus, during the reverse movement of 101, its telephone-line-wire circuits are open in 45 102; during the reverse movement of 103, its line-wire circuits and its guard-wire circuits, which alone can influence any telephone line conductor, are open in 102 and 105; during the ensuing reverse movement 50 of 102, 104 and 105, their line-wire circuits are open in pilot 103 with its brushes on tags 0—and—12.

Pilot brushes on tags 0—and—12 close C24 and switches 102, 104, 105 advance their 55 brushes one step, engage their clutch member upon the next swing of the clutch hooks, and return to normal positions shown in the drawings, closing then C25 which by C4 advances the pilot brushes to position 60 1—and—13 and completes restoration, the switches becoming again electrically dependent for "operating" circuits and being again in readiness for further service in response to a calling telephone line.

C24. "Switch clutch".—(Pilot 0—12). Battery, final-connector magnet 125, normal switch 115, 105—20—23, to wire 330; also, battery, register magnet 124, normal switch 114, 104—6—23, to wire 330; also, group-finder magnet 122, normal switch 112, 70 102—4—23, to wire 330; then wire 330, 103—10—12, earth. If 104 or 105 has not been operated from normal, C24 does not operate that switch.

C25. "Pilot normalizing".—(Pilot 0—12). 75 Battery, helix of 138, wire 350, 103—2—12, wire 335, 105—18—12, 104—3—12, wire 314, 102—3—12 and to earth over wire 328.

Should the selected line be found busy, a potential will be found upon wire 353 with 80 pilot brushes on tags 5—and—17, and current over C26 will charge busy-test relay 137, thus preventing the operation of C14. Pilot brushes will remain on tags 5—and—17 until the receiver of the calling telephone is hung 85 up. Relay 137 will close C27₁ to operate buzzer 135 and also will close C27 by which the buzzer tone currents are carried to the calling telephone.

When the busy-test relay has been operated, a locking circuit C26₁ with an auxiliary release circuit C20₁ in pilot position 6—18 prevents the pilot 103 from stopping in speaking position upon that call.

C26. "Busy test".—(Pilot 5—17). 95 Battery, any resistance 134 or 174, wire 353, switches 105 and 104 as adjusted, wire 323, 103—3—5, wire 376, helix of 137, earth.

C27₁. "Tone primary".—(Pilot 5—17). Battery, helix of 135, points of 135, primary 100 helix of induction coil 136, wire 396, 103—7—17, earth.

C27. "Tone".—(Pilot 5—17). Earth, secondary helix of 136, wire 615, points of 137, wire 340, then over C8 through helix of 142 105 and battery to earth.

C26₁. "Locking".—(Pilot 5—17). Battery, lower helix of 139, wire 317, wire 617, tag and brush 101—17—25 in linefinder as adjusted, wire 608, points of 137, helix of 110 137, earth.

C20₁. "Busy release".—(Pilot 6—18). Battery, helix of 138, wire 350, 103—2—18, wire 614, points of relay 139, earth.

The pilot lamp 194 glows to show an operating division while its brush is upon tag 115, 116 or 17. With the brush on 18, the ringing lamp 195 glows while the relay 140 is uncharged by reason of the receiver of the selected line being on the hook. Pilot 120 lamp 194 glows while its brush moves over tags 19, 20, 21, while its brush waits on tag 23, and while its brush waits on tag 12, thus giving an intermittent signal during restoration of the division.

The calling loop circuit C8 is closed prematurely by a short circuit from 103—4—2 to 103—5—2 while the pilot is in position

2—14, thus giving the relays 141, 142 a preliminary magnetization and avoiding a slow response upon a line loop of high resistance.

Having thus described my invention, what I claim as new and desire to secure by United States Letters Patent is:

1. In combination, an electrical switch, magnets for said switch, means for propelling said switch controlled by said magnets, a prime mover supplying power for restoring said switch, and mechanical means operated by said prime mover independent of electromagnets for preventing the energization of said magnets during the restoration 15 of the switch.

2. In an automatic telephone system, a callsender adapted to create a series of electrical impulses; a switch controlled wholly thereby; a magnet 139 having a first control 20 by impulses from said callsender; and further means, comprising in part parts in said switch, for exercising a secondary control upon said magnet, said magnet controlled contemporaneously from both said callsender 25 and said further means.

3. In an automatic telephone system, a callsender generating a series of electrical currents; a switch controlled by said callsender; a circuit closed repeatedly by control of said 30 callsender; a second circuit closed repeatedly by control of said switch; and a magnet 139 containing in its helices portions of both circuits said circuits controlling said magnet at times contemporaneously.

4. In an automatic telephone system, a callsender generating a series of electrical currents; a switch controlled by said callsender; a circuit closed repeatedly by control of said 40 callsender; a second circuit closed repeatedly by control of said switch; and a changeover device containing a portion of each of said circuits, said circuits effective at times contemporaneously.

5. In an automatic telephone system, a 45 callsender; a selective switch; a changeover device; circuits from said callsender to said selective switch and circuits from said callsender to said changeover device whereby said callsender sends to said switch electrical 50 impulses to operate said switch selectively and whereby said callsender sends to said changeover device electrical impulses for primary control of said changeover device; said switch having full-step positions of selective 55 adjustment and having half-step positions intermediate of its positions of adjustment; and a further circuit closed by said switch in its half-step positions whereby said switch sends to said changeover device electrical 60 impulses for secondary control of said changeover device.

6. In an automatic telephone system, a 65 callsender, a selective switch; a changeover device; said selective switch having selective positions of adjustment and having stop posi-

tions intermediate of its positions of adjustment when its brushes are at the half-step; and a circuit from said switch to said changeover device and preventing the operation of said changeover device while said switch is 70 in an intermediate position.

7. In an automatic telephone system, a callsender; a selective switch having selective positions and half-step stop positions; a changeover device; and means for preventing the operation of said changeover device while said switch is in a half-step 75 position.

8. In an automatic telephone system, a callsender; a selective switch having selective positions and half-step positions; a changeover device; circuits from said callsender to said switch whereby said switch is advanced to half-step position by the beginning of a current under control of said 80 callsender and whereby said switch is advanced from the half-step position by the cessation of a current from the callsender; a circuit from said switch at half-step to said changeover device and broken by said 85 switch when leaving its half-step position, whereby current in said last circuit continues after cessation of current in said first circuits.

9. In an automatic telephone system, a 95 callsender; a selective switch having selective positions and half-step positions; a changeover device; circuits from said callsender to said switch whereby said switch is advanced to half-step position by the beginning of a 100 current under control of said callsender and whereby said switch is advanced from the half-step position by the cessation of a current from the callsender; a circuit from said switch at half-step to said changeover 105 device and broken by said switch when leaving its half-step position, whereby current in said last circuit continues after cessation of current in said first circuits; and further circuits from said callsender to said changeover device.

10. In an automatic telephone system, a callsender and circuits in combination to produce a series of signal currents; a switch and circuits in combination to produce a second series of signal currents, said switch controlled by signal currents from said callsender, said second series of currents being concurrent with said first series of currents and the currents of said second series being 115 out of phase with the currents of said first series; and a changeover device controlled by currents of both series concurrently.

11. In an automatic telephone system, a callsender and circuits in combination to 125 produce a series of signal currents; a switch and circuits in combination to produce a second series of signal currents, said switch controlled by signal currents from said callsender, said second series of currents being 130

- concurrent with said first series of currents and the currents of said second series being out of phase with the currents of said first series; a change-over device controlled by 5 currents of both series concurrently; and a changeover circuit prepared through contacts in said selective switch and closed ultimately by contacts in said changeover device.
- 10 12. In an automatic telephone exchange, selective switches and a pilot switch, said pilot switch having a pre-normal position; contacts in normal positions of said selective switches, respectively; and a normalizing 15 circuit for the pilot by which the pilot may be advanced from pre-normal position to normal position only when the said selective switches are in normal positions.
13. In an automatic telephone exchange, 20 a division of switches containing selective switches and a pilot switch, circuits for advancing said selective and pilot switches to sub-restoring positions; a circuit controlled by the selective switches in sub-restoring positions to advance said pilot switch; means for restoring said pilot to pre-normal position; circuits closed by said pilot in pre-normal position to advance said selective switches; means for restoring said selective 25 switches to normal; and a circuit through said selective switches when normal to advance said pilot to normal.
14. In an automatic telephone exchange, a division of switches containing linefinder, 30 groupfinder and pilot; circuits for advancing said switches for restoration, and means for restoring the groupfinder after the pilot and linefinder have been restored.
15. In an automatic telephone exchange, a 35 division of mechanically similar switches containing linefinder, groupfinder and pilot; circuits for advancing said switches for restoration; and means preventing simultaneous restoration of groupfinder and pilot.
- 40 16. In an automatic telephone exchange; lines; selective switches containing terminals of said lines; a pilot for said selective switches; conductors between the pilot and the selective switches; circuits for advancing 45 said selective switches to positions where said conductors are disconnected from any of said lines; means for restoring said pilot by reverse movement while said conductors are disconnected.
- 50 17. In an automatic telephone exchange; lines; selective switches containing terminals of said lines; a pilot for said selective switches; conductors between the pilot and the selective switches; circuits for advancing 55 said selective switches to positions where said conductors are disconnected from any of said lines; means for restoring said pilot by reverse movement while said conductors are disconnected; and further means for re-
- storing said switches by reverse movement 65 while said conductors are open in said pilot.
18. In an automatic telephone exchange, a pilot switch operable through a plurality of positions, including busy-test position and speaking position; a busy-test relay; a 70 second relay; a locking circuit for said two relays; and a release circuit for said pilot from speaking position and formed by said second relay when locked by said busy-test relay.
- 75 19. In an automatic telephone exchange, a pilot switch, a pilot lamp, a lamp circuit having in the pilot switch connections for causing said lamp to give a continuous glow in each position of the switch when setting up 80 a connection; and further circuit connections in the pilot switch for causing said lamp to glow intermittently during the actions of release and restoration of the pilot switch.
20. In an automatic telephone system, a 85 pilot switch constituting a change over device; a changeover relay co-operating with said pilot switch to produce changeover; a numerical switch; a callsender; circuits controlled by said callsender to said relay and 90 to said numerical switch; a circuit controlled by said numerical switch to said relay; and a circuit through contacts of said relay and said numerical switch to said pilot switch.
- 95 21. In an automatic telephone system, a pilot switch constituting a changeover device; a changeover relay co-operating with said pilot switch to produce changeover; a numerical switch; a callsender; a signal relay controlled by said call sender circuits 100 controlled by said signal relay to said changeover relay and to said numerical switch; and a circuit controlled by said numerical switch to said changeover relay; the currents in said two circuits being concurrent but out of phase.
- 105 22. In an automatic telephone system, automatic switches, each having a tag bank and a set of movable brushes, said brushes having normal and off-normal positions; a starting circuit for said switches; normal tags in each switch through which, when said brushes are in normal position, said starting circuit may pass to apparatus associated with said switch; and other tags in 110 each switch, through which said circuit may be continued independently of apparatus associated with said switch, when said brushes are in certain position other than normal, said switches otherwise independent.
- 115 23. In an automatic telephone system, a telephone line; relays responsive to currents over said line; an automatic switch; and a short circuit between automatic switch elements and causing initial charge of said relays before said relays are connected to said line.
- 120 24. In an automatic telephone system, a

telephone line; relays responsive to currents over said line; and a circuit over conductors local to the central office and providing a path for current through said relays for initial charge before said relays are connected to said line.

25. In combination, a prime mover, a shaft driven by said prime mover; switches; circuits for advancing said switches; parts in said switches for engaging said shaft for restoring said switches, said parts opening said circuits in each switch being restored.

26. In combination, a prime mover, switches, a power shaft associating said prime mover with said switches; means for restoring a switch by said prime mover; a

circuit for advancing a switch, said circuit being rendered inoperable by said prime mover during restoration of said switch and until after disengagement of said prime mover from said switch after restoration.

27. In combination, an electrical switch comprising fixed parts and a movable brush carriage; a main spring propelling said brush carriage in its movement of selection; a power shaft, and a single power-transmitting link connecting said shaft and said brush carriage at times to restore said brush carriage.

Signed by me at Toronto, county of York, 30 and Province of Ontario, Canada.,

DAVID S. HULFISH.
